UNITED STATES PATENT OFFICE.

ORVAL L. WILLIAMS, OF KENMORE, OHIO.

RAIL JOINT.

Application filed January 15, 1927. Serial No. 161,295.

This invention relates to rail joints.

The general purpose of the invention is to provide an improved rail joint in which boltless joint bars are employed which are 5 interchangeable on either side of the rail and which are designed to effectively hold the rail ends in place.

This purpose is attained by the rail joint construction illustrated in the accompanying drawings and described below. It is to be understood that the invention is not limited to the specific form thereof shown and described.

Of the accompanying drawings,

15 Figure 1 is a side elevation of a rail joint embodying the invention;

Figure 2 is a plan thereof; and

Figure 3 is a section on line 3—3 of Figure 2.

20 Referring to the drawings, the numerals 10, 10 designate the ends of adjoining rail sections and the numerals 11, 11 the improved joint bars of the invention, each being of identical construction so as to be 25 capable of use on either side of the rail interchangeably.

Each bar 11 is formed with an upright member 12, the upper edge of which indicated at 13 is arranged to engage beneath 30 the rail head and against the rail web; a foot flange 14 which is arranged to overlie and contact with a rail flange; and an inwardly extending base member 15 is arranged to underlie and engage the base of 35 a rail.

The upright member 12 is adapted to fit the fishing space of the rail, the inner face of said member being beveled as indicated at 12^a so as normally to be out of contact 40 with the rail excepting at its upper edge. The base member 15 is also beveled as at 15^a so as normally to be out of contact with the base of the rail excepting at its inner edge as indicated at 15^b. Clearance is provided 45 at 16 between the edge of the rail flange and the joint bar 11. This construction is such that the weight of a car on the rail 10 will tend to rock the upright members 12 inwardly the more firmly to grip the rail 10 at 18, 13.

50 For securing the joint bars in place with spikes or the like, the base members 15 are laterally extended and spike apertures 17, 17 are formed in the extended portions thereof.

Instead of employing the usual securing

bolts, each joint bar 11 is formed with a pair of integral pins 18 and 19 so arranged thereon that one pin 18 adjacent the center of each bar is adapted to project through the standard bolt aperture 20 adjacent the end of each rail section and the other pin 19 adjacent the end of each joint bar is adapted to project through the other standard bolt aperture 21 more remote from the end of each rail section 10. Preferably, but not necessarily, the pins 18 and 19 are elongated so as to extend through apertures 22, 22 formed in each joint bar in alignment with the pins 18 and 19 of an opposite joint bar. Additional security may be provided by use of taper keys 23, 23 in the ends of pins or studs 18 and 19 with lock washers 24, 24 for preventing loosening of the pins or instead of using keys 23, the ends of pins or studs 18 and 19 may be bent as indicated in dotted lines in Figure 3. The bending of pins or studs 18 or 19 can also be done, as indicated, as an additional precaution to the use of keys 23.

55 In the preferred form of the invention, the joint bar 11 is formed with integral bracing ribs 25, 25 preferably in line with pins 18 and 19 on the outer side of the bar and extending between upright members 12 and base members 14.

The joint bars for providing a joint such as described above are all identical so that manufacture of the bars in pairs may be avoided. Nevertheless they may be effectively secured to the rail ends and to each other to properly and securely join the rail ends.

90 Modifications of the invention may be resorted to without departing from the spirit thereof or the scope of the appended claims.

95 What is claimed is:

1. A rail joint including the rail and similar joint bars on opposite sides of the rail connecting adjoining ends of the rail sections, each joint bar comprising an upright member for fitting the fishing space, the inner face of said member being beveled to clear the rail excepting at the top edge thereof, the top edge of the upright member being arranged to engage under the rail head and against the rail, a foot flange for resting on the rail flange, a base member for engaging under the base of the rail and beveled on its upper face so as normally to contact the base of the rail only at its inner edge, pairs of integral studs, one stud of

each joint bar being arranged to project through an aperture in a rail section adjacent its end and an aperture in the adjoining rail section more remote from its end, each 5 joint bar having apertures therein adapted to be aligned with the studs on an opposite joint bar, said studs being elongated so as to extend through the rail and through the apertures in the opposite joint bar, taper 10 key means on the studs for securing the joint bars to the rail and to each other, and reinforcing ribs between the upright member and the base member on the outer sides of the joint bars, said ribs being aligned 15 with the studs on said bars.

2. A rail joint including the rail and similar joint bars on opposite sides of the rail connecting adjoining ends of the rail sections, each joint bar comprising an upright 20 member for fitting the fishing space, the inner face of said member being beveled to clear the rail excepting at the top edge thereof, the top edge of the upright member being arranged to engage under the rail head and against the rail, a foot flange for 25 resting on the rail flange, a base member for engaging under the base of the rail and beveled on its upper face so as normally to contact the base of the rail only at its inner 30 edge, pairs of integral studs, one stud of each joint bar being arranged to project through an aperture in a rail section adjacent its end and an aperture in the adjoining rail section more remote from its end, each 35 joint bar having apertures therein adapted to be aligned with the studs on an opposite joint bar, said studs being elongated so as to extend through the rail and through the apertures in the opposite joint bar, taper 40 key means on the studs for securing the joint bars to the rail and to each other, and reinforcing ribs between the upright member and the base member on the outer sides of the joint bars.

45 3. A rail joint including the rail and similar joint bars on opposite sides of the rail connecting adjoining ends of the rail sections, each joint bar comprising an upright member for fitting the fishing space, the inner face of said member being beveled to clear the rail excepting at the top edge thereof, the top edge of the upright member being arranged to engage under the rail head and against the rail, a foot flange for 50 resting on the rail flange, a base member for engaging under the base of the rail and beveled on its upper face so as normally to contact the base of the rail only at its inner edge, pairs of integral studs, one stud of each joint bar being arranged to project through an aperture in a rail section adjacent its end and an aperture in the adjoining rail section more remote from its end, said 55 studs being elongated so as to extend through the rail and through the apertures in the opposite joint bar.

each joint bar being arranged to project 60 through an aperture in a rail section adjacent its end and an aperture in the adjoining rail section more remote from its end, each joint bar having apertures therein adapted to be aligned with the studs on an 65 opposite joint bar, said studs being elongated so as to extend through the rail and through the apertures in the opposite joint bar, and taper key means on the studs for securing the joint bars to the rail and to 70 each other.

4. A rail joint including the rail and similar joint bars on opposite sides of the rail connecting adjoining ends of the rail sections, each joint bar comprising an upright 75 member for fitting the fishing space, the inner face of said member being beveled to clear the rail excepting at the top edge thereof, the top edge of the upright member being arranged to engage under the rail head and against the rail, a foot flange for 80 resting on the rail flange, a base member for engaging under the base of the rail and beveled on its upper face so as normally to contact the base of the rail only at its inner 85 edge, and pairs of integral studs, one stud of each joint bar being arranged to project through an aperture in a rail section adjacent its end and an aperture in the adjoining rail section more remote from its 90 end, each joint bar having apertures therein adapted to be aligned with the studs on an opposite joint bar, said studs being elongated so as to extend through the rail and through the apertures in the opposite joint 95 bar.

5. A rail joint including the rail and similar joint bars on opposite sides of the rail connecting adjoining ends of the rail sections, each joint bar comprising an upright 100 member for fitting the fishing space, the inner face of said member being beveled to clear the rail excepting at the top edge thereof, the top edge of the upright member being arranged to engage under the rail head and against the rail, a foot flange for 105 resting on the rail flange, a base member for engaging under the base of the rail and beveled on its upper face so as normally to contact the base of the rail only at its inner 110 edge, and pairs of integral studs, one stud of each joint bar being arranged to project through an aperture in a rail section adjacent its end and an aperture in the adjoining rail section more remote from its end, said 115 studs being elongated so as to extend through the rail.
